Primary Examiner — Jennifer Rivard*Assistant Examiner* — Jenny lou M Binas(57) **CLAIM**

The ornamental design for an electric spin scrubber, as shown and described.

DESCRIPTION

FIG. 1 is a perspective view of an electric spin scrubber design showing my new design.

FIG. 2 is a top view of an electric spin scrubber.

FIG. 3 is a bottom view of an electric spin scrubber.

FIG. 4 is a left side view of an electric spin scrubber.

FIG. 5 is a right side view of an electric spin scrubber.

FIG. 6 is a front view of an electric spin scrubber.

FIG. 7 is a rear view of an electric spin scrubber; and, FIG. 8 is an exploded perspective view of the electric spin scrubber showing an alternative head.

The broken lines shown in the drawings are for the purpose of illustrating portions of the electric spin scrubber that form no part of the claimed design.
